DESIGN FOR A PICTURE FRAME

Edward O'Toole, New York, N. Y.

Application September 10, 1937, Serial No. 71,556

Term of patent 14 years

To all whom it may concern:

Be it known that I, Edward O'Toole, a citizen of the United States, residing at New York, county and State of New York, have invented a new, original, and ornamental Design for a Picture Frame, of which the following is a specification, reference being had to the accompanying drawing, forming a part thereof.

The figure is a front perspective view of a picture frame embodying my design.

I claim:

The ornamental design for a picture frame, substantially as shown.

EDWARD O'TOOLE.
